ROCKING CHAIR

Joseph Rodd, 783 E. 11th St., New York, N.Y.

Filed Nov. 28, 1962, Ser. No. 72,634

Term of patent 3½ years

(Cl. D15—6)

The appearance of the chair back is like the front thereof, and the undisclosed side of the chair is like the illustrated side.

I claim:

The ornamental design for a rocking chair, substantially as shown and described.
